BRAUN TUBE, MORE PARTICULARLY FOR
TELEVISION PURPOSESKurt Schlesinger, Berlin, Germany, assignor, by
mesne assignments, to Loewe Radio, Inc., a cor-
poration of New YorkApplication December 5, 1934, Serial No. 756,126
In Germany December 9, 1933

6 Claims. (Cl. 250—162)

In Patent No. 2,126,286 to K. Schlesinger there is described a Braun tube for television purposes, in which electron-optical systems are employed, which consist of suitable combinations of electrostatic electron-optical collecting and dispersing lenses.

The present invention relates to further developments of Braun tubes comprising electron optical systems.

10 The invention relates to a particular embodiment of the electron-optical systems and to Braun tubes furnished with systems of this character.

According to the invention, there are employed for producing the electrostatic fields acting as 15 collecting and/or dispersing lenses cylindrical elements which are raised to different potentials.

20 In accordance with the invention, the refractive power of the electron-optical lenses may be adjusted as desired by varying the biases and the spacial relation of the two cylinders and by selection of the cylinder diameter.

25 If it is desired that the refractive power of the one electron-optical lens should be less than that of the other, the diameter of the cylinder corresponding with this lens is, in accordance with the invention, considerably increased, so that in the same a practically fieldless space results. Instead of reducing the diameter of the other cylinder it is also possible to close the particular cylinder by means of a diaphragm having an aperture, the diameter of which is smaller than the diameter of the cylinder.

30 If—as for example in the case of amplifier tubes according to the transverse field principle—concentration of the bundle of electrons is necessary only in one direction, the cylinders, in accordance with the invention, may be replaced in equivalent fashion by pairs of condenser plates or preferably by metallic boxes.

35 40 The present invention may be best understood by referring to the drawings wherein—

Figures 1 through 5 illustrate the effect of electrostatic fields to produce an electron lens, and

45 Figures 6 through 10 show the incorporation of electron lenses in the path of an electron beam.

50 1 and 2 are in each case the two cylinders, and 3 closure diaphragms. By the number of “+” signs there is indicated the state of charge of the elements concerned, in such fashion that the greatest number of “+” signs indicate the maximum positive potential.

55 The arrangement in Fig. 1, if the cylinder 1 is connected with a weaker positive potential than

the cylinder 2, acts as combination of a collecting lens with a dispersing lens of equal power. Reversal of the two refractive effects may be accomplished simply by reversing the biases.

In numerous cases it is desirable to make one 5 of the two refractive forces smaller than the other.

According to the invention, this may be accomplished for example, by a considerable increase in the diameter of that particular tubular 10 system in which a practically fieldless, i. e., ineffective space is to be produced, as shown in Fig. 1a. In Fig. 1a the diameter of the inlet tube 1 is considerably smaller than the diameter of the outlet tube 2. In this manner it is accomplished that the focal distance of the collecting 15 lens is shorter than the focal distance of the dispersing lens.

Additional arrangements according to the invention for obtaining a predominantly one-sided 20 refractive effect, i. e., for increasing the focal distance of one of the two lenses, are illustrated by way of example in Figs. 2-5.

In these lenses the reduction in cross-section 25 takes place by means of a diaphragm-like element 3, which is linked up with the same potential as 1 or 2 dependent on the fact as to whether the focal distance of the collecting lens or that of the dispersing lens is to be reduced.

As apparent from the record of the appertain- 30 ing potential line and field line diagrams, the ray in the case of these arrangements is acted upon primarily only in the space between the diaphragm 3 and the tubular portion not connected therewith, whilst owing to the small field 35 reciprocal in the space of same potential enclosed by the diaphragm 3 variations in the direction of the ray in this latter may be ignored. This applies all the more the smaller the diameter of the diaphragm aperture in relation to the 40 diameter of the tube and the greater the distance between the ends of the tube. The diameter of the diaphragm aperture determines the greatest effective aperture of the lens.

The arrangement according to Fig. 2, if the 45 ray passes from the left to the right and 1 is connected with a lower potential than 2, acts in the manner of a collecting lens within 1 with simultaneous acceleration.

The arrangement according to Fig. 3, with sim- 50 ilar supply of the potential, acts as a dispersing lens with simultaneous acceleration.

The arrangement according to Fig. 4, with sup- 55 ply of the potential as stated, acts as dispersing

lens with retardation within 1, whilst the arrangement illustrated in Fig. 5 acts as collecting lens with simultaneous retardation within 2.

As an example of the use of the lenses according to the invention there are described in the following two constructions of television tubes.

In tubes of this nature there exists the problem of reproducing sharply the aperture of a diaphragm 4 in an image-screen plane 5 as far as possible on reduced scale. The most simple arrangement for solving this problem consists of a collecting lens disposed as closely as possible to the screen 5 and as far away as possible from the diaphragm aperture 4. Since it is necessary to impart to the electrons when reaching the screen the highest potential capable of being supplied by the potential source (in order to obtain maximum intensity of light), there is suitable for this purpose a collecting lens, which acts as accelerating lens, i. e., which simultaneously imparts to the ray an acceleration.

A lens of this nature is illustrated in Fig. 6. The same consists of a tubular member 7, which is as wide as possible and accordingly permits of the use of thick bundles, in front of a diaphragm 8 which somewhat reduces the cross-section, 7 having a lower potential (+) than the diaphragm 8 (++).

If the diaphragm 8 with its reduction of cross-section is omitted, there is formed, subject to at least partial conductivity (for example provision of a metallic coating) and charging of the wall of the bulb 9 to the high potential (++) a combined lens system corresponding with Fig. 1, in which following on a collecting lens, which is to be considered as being arranged in the tube 7, there is a dispersing lens, which is to be regarded as being localised in the bulb portion 9. Assuming that the diameter of the part 9 is larger than the diameter of the tube 7, an arrangement of this nature also acts primarily as collecting lens according to Fig. 1a; the same, however, possesses the disadvantage of decrease of the refractive power with large displacement of the bundle of rays out of the axis.

By combination of a dispersing lens with a collecting lens, which may be arranged at a relatively large distance apart, it is possible according to the invention with the same length of tube 50 to obtain a better reduction of the image point than occurs in the case of the single-lens tube described in Fig. 6 (reversed tele-objective).

In Figs. 7 and 8 there are shown two forms of embodiment of Braun tubes according to the invention, making use of the accelerating or retarding lenses described in Figs. 1-5.

As shown in Fig. 7, there is employed a diaphragm 4, which is lighted for example by means of the condenser arrangement described in the following and is preferably connected with a comparatively low positive potential (for example 100 volts).

The total length of the tubular portion up to the point 6 (i. e., up to the collecting lens) may be the same as in the case of the single-lens tube according to Fig. 6. At this point 6 there is provided in accordance with the invention a final anode raised to the highest potential occurring (++) and having an aperture exceeding the largest cross-section of bundle. A tubular portion 10 of approximately half the total length of tube 5% available is linked up with the potential of the diaphragm 4 (+). Between 10 and 6 there is provided an additional tubular portion 11, which joins up with the tubular portion 10 and

to which there is imparted a medium potential (++) . There is then formed between 10 and 11 in the manner indicated in broken lines a dispersing lens with simultaneous acceleration according to the diagram of Fig. 3, and between 5 the tubular portion 11 and the main anode 6 a collecting lens with additional acceleration according to the diagram in Fig. 2.

To explain the passage of the rays obtained by the arrangement there is shown in the drawings an arrow 12 in substitution for the object (diaphragm aperture 4). Of this there is produced in the manner stated by the dispersing lens 13 a reduced virtual image 14 on the side directed towards the object, i. e., within the 15 tubular portion 10. By suitable selection of the focal distance of the collecting lens 15 there is projected in the plane 5 of the luminous screen a reversed, correct reproduction 16 from the image 14. This image is considerably smaller than 20 the images capable of being obtained with the same length of tubular member when employing solely a collecting lens (image 17). The adjustment of the focal distances, with given geometric dimensions, may be performed in simple fashion according to the invention by adjustment of the relative differences in potential between the mutually insulated electrodes forming the particular lens (1% on the one hand and 1% on the other hand).

A tube having the same electronic optic but with different accelerating and retarding conditions is illustrated in Fig. 8. In this arrangement also a diaphragm aperture 4 is lighted with a bundle of electrons as parallel as possible. Connected with 4 is a tubular portion 10 raised to medium potential (++) . Opposite the opening of the tubular portion 10 there is situated a diaphragm 18, which is insulated against the same, and with which the tube 11 is connected and raised to the lower potential (+). In front of the latter tube there is provided an anode 6 raised to the maximum potential available (++) . There is again obtained a dispersing lens in the indicated position 19, which acts as 40 retarding lens on the lines of Fig. 4, and a collecting lens 20 with simultaneous acceleration on the lines of Fig. 2.

A further object of the invention are means for lighting the small diaphragm aperture 4 representing the object to be reproduced with the greatest possible density of light and smallest possible opening of the bundle of rays. The latter requirement is particularly important in tubes according to Figs. 7 and 8, which operate with combined lens systems, as in tubes of this nature a bundle which already diverges in the diaphragm aperture 4 may assume such an expanse that at the point of the final concentration lens (15 or 20 in Figs. 7 and 8 respectively) it is not fully embraced by the lens aperture and, therefore, is weakened in part by selection. Since the bundle leaving the lens takes up merely a small angle in space about the axis of the tube, it is furthermore possible in accordance with the invention to approach the deflecting plates very closely together without curving off the bundle. It is accordingly possible with prescribed maximum angle of deflection to employ short plates, and in this manner a high 50 sensitivity of deflection and considerable diminishment of the marginal fields is obtained.

There accordingly exists in this connection as continuously recurring problem (see Fig. 9):

There is a cathode 21 of a given kind, the sur- 75

face of which is determined by the desired maximum emission (spot of oxide of the order of approximately .5-1 mm.²). This spot of oxide for the purpose of producing defined potential areas is such into a piece of metal 22, the surface of which is larger than that of the oxide and is, for example, ground flat. At a distance 23 in front of this cathode which is freely selective in itself there is provided the diaphragm 4 having a very small aperture (for example also .5 mm.), which is raised to a positive potential (+++) as prescribed by the remaining electron-optical system and the maximum existing anode potential. It is necessary that as large a fraction as possible (in the ideal case 100%) of the flow of electrons from the cathode 21 should pass through the small aperture of 4. Heretofore it has been attempted to solve this problem by projecting within the diaphragm aperture of 4 a true reproduction of equal or reduced size of the cathode surface 21 by means of a collecting lens (24) disposed between the same and the diaphragm 4. The disadvantage of this method consists fundamentally in the fact that although it is possible to pass all rays through 4 these rays take up an excessively large angle of divergence and accordingly are lost in part in the rear sections of the extended optic by selection outside of the reproducing lenses provided at that point.

In the above-referred to Patent No. 2,126,286 it has already been set forth in detail that there may be employed with advantage an electron-optical combination of two lenses, viz., a collecting lens 24 and a dispersing lens 25 following thereon, 24 causing the actual reproduction of the cathode on the diaphragm aperture, whilst 25 imparts dispersion to the rays shortly in front of the diaphragm aperture, which dispersion causes the rays to pass through the diaphragm in practically parallel form. The better this problem is solved, i. e., the smaller the diaphragm apertures 4, lighted without loss, may be made with a given cathode surface 21, the shorter are the television tubes, and the more parallel the bundle of rays is made the greater may be the dispersions employed in the method according to Figs. 7 and 8 without the bundle afterwards possessing an inadmissibly great cross-section. These features all assist towards a reduction in the structural length of the tube and in an improvement in the sensitiveness of deflection by increase of the ratio between deflected length of ray and tubular length of ray with given size of image field and image point.

According to the invention, there are also employed for lighting the diaphragm arrangements on the lines of the systems described at the commencement. This may take place, for example, in the following manner:

At as short a distance as possible from the cathode surface 22 there is provided a suctional anode 26 having a comparatively large aperture, for example 2-3 mm. According to the invention, the combination of the two lenses 24, 25 is produced by a double-cylinder arrangement without intermediate diaphragms on the lines of the arrangement illustrated in Fig. 1, in such fashion that a cylinder 27 is placed opposite to a second cylinder 28 of the same diameter. These cylinders are distinctly determined both as regards their length as well as their diameter by the potential prevailing at the diaphragm 4 and by the size of this diaphragm and of the spot of oxide. If it is desired that in addition to the con-

centration effect always present in the front tubular member 27 the dispersing lens 25 should also fully develop, the length of the second tubular member 28 should at least be equal to and preferably greater to the extent of approximately twice the amount than the length of the front tubular member 27, as may be proved by making a record of the potential line diagram. On the other hand it has been found convenient according to the invention to connect the front tubular member 27 electrically with the suctional anode 26, and also the rear tubular member 28 with the diaphragm 4, as in this manner the formation of additional lens fields at the transition points between the stated electrodes is avoided. Assuming the bias of the diaphragm 4 to be approximately 300 volts (+++), as will be the case, for example, in a tube according to Fig. 6 with altogether 2000 volts anode potential and a scale of reproduction of 1:1, the potential of the suctional anode 26 as well as that of the front tubular member 27 must be lower than 300 volts (+).

It is desirable according to the invention not to make the potential at 27 too low in order to prevent reduction of the emission.

The passage of the ray in the condenser is determined by the ratio between the radial field intensity and the particular speed of the electrons.

According to the invention, the former is increased by reducing in proportion the entire diameter and longitudinal dimensions of the condenser. With biases maintained constant all field intensities in the interior of the condensers are thus increased in proportion. In this manner it is possible to reduce the requisite difference in potential between the suctional anode 26 and the diaphragm 4, and to increase the difference in potential between the suctional anode (+) and the cathode (with the potential zero).

The arrangement may be dimensioned, for example, as follows:

Cylinder diameter of 27 and 28: 10 mm. In this connection 27 was 10 mm. in length and 28 was 20 mm. in length. Cathode 21: .3 mm. diameter. Diaphragm aperture: .5 mm. diameter. Length of tube: 500 mm. In this connection the potential at 4 was 300 volts (+++). Potential at 26: 30 volts. By reducing the diameter and length of the cylinders to one-half or one-third the potential at 26 may be raised to approximately twice to three times the amount, and in this way the maximum emission of the arrangement increased accordingly.

A condenser arrangement of this character, as illustrated by way of example in Fig. 9, may be controlled in faultless manner as regards its intensity by means of a diaphragm-like control grid 29 through the medium of a control potential source 30, without the diameter of the bundle and the angle of divergence being appreciable varied behind the diaphragm. The control grid 29 may in practice also possess a greater diameter than the cathode (1-2 mm.) and is preferably approached as near towards the spot of oxide as possible in order to increase the steepness of the control. According to the invention, the same may be arranged at a distance of approximately 1 mm. or even less from the cathode 21 and suctional anode 26. The applicant has already set forth on a previous occasion the manner in which an arrangement of this nature may be centred mechanically. The cyl-

- inders 27 and 28 are conveniently engaged by set-on collars 4 and 26, and the latter centred in relation to each other by means of common glass rods 31 passing through borings in these collars.
- 5 In place of the rods there may also be employed glass tubes, and in the borings thereof the leads to other parts of the system arranged in insulated fashion. These measures are of particular importance as regards the arrangement according 10 to the invention, as it is a matter of axially centring a condenser system of this nature which is precisely concerned owing to the appreciable increase angularly in the lack of symmetry later taking place.
- 15 It will be quite obvious that the sizes and potentials are quoted merely by way of example, and require to be varied accordingly when changing the measurements of the tube or the operating potentials.
- 20 Both the condenser optic as well as reproducing optic according to the invention may be employed quite readily in Braun tubes of a desired kind, and more particularly high-vacuum tubes for television purposes, and also other discharge 25 vessels, for example amplifier tubes according to the transverse field principle.
- It is also quite readily possible to modify the stated forms of embodiment in their details without departing from the fundamental idea of the 30 invention.
- There shall be remarked that it may be possible in some cases to replace a cylinder having an apertured diaphragm by an apertured plate of corresponding dimensions.
- 35 In the preferred embodiment of the invention a Braun tube may contain the combination of a first electron-optical system for example as shown in Fig. 9 with reproducing system, for example, as shown in Figs. 6-8, as illustrated by way 40 of example in Fig. 10 which shows, within an envelope, an electrode structure according to the invention in an entirely diagrammatic fashion, means being provided for supplying the different electrodes with the necessary potentials. Such 45 means may consist in a manner known per se of one or more potential sources. If one potential source, for example, a battery, be used, the same may be bridged by a potentiometer having several tappings which correspond to the different required voltages. Different elements having 50 to be supplied with the same bias may be connected inside the tube with one another. The Braun tube further comprises a picture receiving screen and deflecting means such as two pairs 55 of deflecting plates for the purpose of scanning said screen. The deflecting means may be such that they are not able to produce a disturbance of the electric concentrating field. In the case that electro-static deflecting systems be used, to 60 the one plate of each deflecting system the deflecting voltage and to the other plate a voltage should be applied, which is equal to said deflecting voltage as to its potential, but which is of reverse phase. With the use of such systems 65 disturbances of the concentrating field easily may be avoided.

The electron-optical systems of the invention follow approximately the formula

$$70 \quad \frac{1}{\psi} = \frac{1}{a} + \frac{1}{b}$$

wherein ψ is the focal distance and a and b the distances of the system from the object point and from the image point, i. e., from the screen. All 75 of the distances may be selected with the use

of this formula, though—the focal distance being adjustable at will—these distances determine the size of the image point only.

I claim:

1. In a cathode ray tube comprising means 5 for producing a cathode beam, a diaphragm having an aperture disposed in the path of the cathode beam, a beam receiving target and means for producing in the space between said diaphragm and said target an electron-optical 10 lens field for producing on said target an electron image of the aperture in said diaphragm, means for preconcentrating the electron beam onto the aperture in said diaphragm comprising two coaxial cylindrical elements of substantially 15 equal diameter displaced axially on the side of said diaphragm remote from said target, the whole cross-section of said cylindrical elements being open at their ends facing each other, said two cylindrical elements positioned coaxially 20 with respect to the aperture in said diaphragm, said two cylindrical elements being adapted to have different potentials impressed thereon to produce the combination of a converging and a diverging electron lens. 25

2. In a cathode ray tube comprising means including an electron source for producing a cathode beam, a diaphragm having an aperture disposed in the path of the cathode beam, a cathode ray intensity control electrode, said 30 cathode ray intensity control electrode being mounted in the vicinity of said source between said source and said diaphragm, a beam receiving target and means for producing in the space between said diaphragm and said target an electron-optical lens field for producing on said target an electron image of the aperture in said diaphragm, means for preconcentrating the electron beam onto the aperture in said diaphragm comprising two co-axial cylindrical elements of substantially equal diameter displaced axially 35 between said control electrode and said diaphragm and positioned substantially coaxially with respect to the aperture in said diaphragm, the whole cross-section of said cylindrical elements being open at their opposed ends, said two cylindrical elements being adapted to have different substantially fixed potentials impressed thereon to produce the combination of a converging and a diverging electron lens. 50

3. In a cathode ray tube comprising means including an electron source for producing a cathode beam, a diaphragm having an aperture disposed in the path of the cathode beam, a cathode ray intensity control electrode, said cathode 55 ray intensity control electrode being mounted in the vicinity of said source between said source and said diaphragm, a beam receiving target and means for producing in the space between said diaphragm and said beam receiving target an electron optical lens field for producing on said target an electron image of the aperture in said diaphragm, means for preconcentrating the electron beam onto the aperture in said diaphragm comprising two coaxial cylindrical elements of substantially equal diameter displaced axially between said control electrode and said diaphragm and positioned coaxially with respect to the aperture in said diaphragm, the whole 60 cross-section of said cylindrical elements being open at their ends facing each other, said two cylindrical elements being different in length and adapted to have different substantially constant potentials impressed thereon to produce 65 70 75

the combination of a converging and a diverging electron lens.

4. A cathode ray tube comprising means including an electron source for producing a cathode beam, a diaphragm having an aperture disposed in the path of the cathode beam, means for preconcentrating the electron beam onto the aperture in said diaphragm comprising two coaxial cylindrical elements of substantially equal diameter displaced axially between said source and said diaphragm, said two cylindrical elements having the aperture in said diaphragm centrally aligned therewith, said two cylindrical elements being adapted to have different potentials impressed thereon to produce the combination of a convergent and a divergent electron lens, a beam receiving target at the end of the cathode ray tube remote from said source, and an electron-optical system mounted between said diaphragm and said target for electron optically reproducing the aperture in said diaphragm on said target, said electron-optical system comprising two axially displaced tubular members positioned coaxially with respect to said cylindrical elements and between said diaphragm and said beam receiving target, and an apertured plate mounted adjacent the end of each of said tubular members facing said beam receiving target.

5. A cathode ray tube comprising means including an electron source for producing a cathode beam, a diaphragm having an aperture disposed in the path of the cathode beam, means for preconcentrating the electron beam onto the aperture in said diaphragm comprising two axially displaced coaxial cylindrical elements of substantially equal diameter mounted between said source and said diaphragm, said two cylindrical elements being positioned coaxially with respect to the aperture in said diaphragm, said two cylindrical elements being adapted to have different potentials impressed thereon to produce the combination of a convergent and a divergent elec-

tron lens, a beam receiving target at the end of the cathode ray tube remote from said source, and an electron-optical system mounted between said diaphragm and said target for electron optically reproducing the aperture in said diaphragm on said beam receiving target, said electron-optical system comprising two axially displaced tubular members mounted coaxially with respect to said cylindrical elements and positioned between said diaphragm and said beam receiving target, and an apertured plate mounted adjacent the end, facing said beam receiving target, of each of said tubular members in a cross-section of the cathode ray tube which is disposed at most as far from said target as the said ends facing said target.

6. In a cathode ray tube comprising means including an electron source for producing a cathode beam, a diaphragm having an aperture disposed in the path of the cathode beam, one, and one only, cathode ray intensity control electrode, said cathode ray intensity control electrode being mounted in the vicinity of said source between said source and said diaphragm, a beam receiving target and means for producing in the space between said diaphragm and said target an electron-optical lens field for producing on said target an electron image of the aperture in said diaphragm, means for preconcentrating the electron beam onto the aperture in said diaphragm comprising two coaxial cylindrical elements displaced axially between said control electrode and said diaphragm and positioned substantially coaxially with respect to the aperture in said diaphragm, the whole cross-section of said cylindrical elements being open at their opposed ends, said two cylindrical elements being adapted to have different constant potentials impressed thereon to produce the combination of a converging and diverging electron lens.

KURT SCHLESINGER.
